(57) **CLAIM**

The ornamental design for a housing for the torsion element of a strut, as shown and described.

DESCRIPTION

FIG. 1 is a perspective view of a housing for the torsion element of a strut according to our invention;

FIG. 2 is a right side elevation thereof;

FIG. 3 is a left side elevation thereof;

FIG. 4 is front elevation thereof;

FIG. 5 is rear elevation thereof;

FIG. 6 is a top plan view thereof;

FIG. 7 is a bottom plan view thereof; and,

FIG. 8 is a sectional view of the housing for the torsion element of a strut according to our invention in the use environment.

The broken line showings are for the purpose of illustrating environment and form no part of the claimed design.

1 Claim, 5 Drawing Sheets
